UNITED STATES PATENT OFFICE.

FRANK J. REICHMANN, OF CHICAGO, ILLINOIS.

COUPLER DEVICE.

Application filed January 24, 1921. Serial No. 439,442.

To all whom it may concern:

Be it known that I, FRANK J. REICHMANN, a citizen of the United States, residing at 4801 S. Morgan Street, Chicago, in the 5 county of Cook and State of Illinois, have invented a new and useful Improvement in Coupler Devices, of which the following is a specification.

My invention relates, more particularly, 10 to coupler devices intended for use more especially in connection with power propelled trackless trailer-vehicles, for coupling them together, and more particularly of the type presenting relatively widely spaced 15 points of pivoted support on the vehicle carrying the coupler device and a single point of engagement with an adjacent vehicle for coupling the two vehicles together.

My primary objects are to provide a 20 coupler device which shall be so constructed that the maximum strength of the metal of which the coupler is made may be utilized, thereby economizing in the cost of producing the coupler device and minimizing its 25 weight; and to provide a coupler device which will remain in coupled condition even when the vehicles coupled together thereby are moving over uneven surfaces; and other objects as will be manifest from the following 30 description.

Referring to the accompanying drawings:

Figure 1 is a plan view of a coupler device constructed in accordance with my invention, the device being shown as in coupling engagement with a keeper, the coupler-device and keeper being shown as provided on adjacent trailer-vehicles represented diagrammatically in plan section. Figure 2 is a view in side elevation of the 40 coupler device and keeper of Fig. 1, showing the trailers diagrammatically in section, the coupler-device being shown by full lines in coupled condition and by dotted lines in the raised position it assumes when out of 45 coupling position; and Figure 3, a perspective view of the coupler device of the preceding figures.

According to my invention the coupler-device is formed of a pair of strips 4 of the 50 same length having the front of the same length, represented at 5, closely adjacent to each other and their rear extremities, represented at 6, in relatively widely spaced relation. The forward ends 5 are preferably 55 flatwise opposed, the rear ends 6 parallel

and their intermediate portions 7 straight, but disposed in divergent condition as shown, the rear ends preferably containing elongated slots 8. The strips 4 are relatively narrow and are so positioned that their 60 longer dimension extends substantially vertically as shown.

The coupler device is also formed of a plate, or head, section 9 which is interposed between the front end sections 5 of the strips 65 4 and in such condition is rigidly secured to the strips, as by means of rivets 10 extending through the strips 4 and the section 9. The section 9 is formed with two hook-portions 11 and 12 which extend lengthwise 70 of the section 9 and toward each other, the hook 11 being longer than the hook 12 and presenting the front convex surface 13 and the rear concave surface 14, the hook 12 presenting a front concave surface 15. 75

The coupler device in the particular construction shown is adapted to be pivotally supported at its slots 8 on a rod 16 which is supported in ears 17 extending outwardly from, and lengthwise of, the vehicle to which 80 it is to be attached, as for example that diagrammatically represented at 18, the parts being preferably so constructed and arranged as shown that while the coupler device is free, in the full-line position shown 85 in Fig. 2, to rock, without binding or wedging, on the vehicle to which it is attached, in the travel of the coupled vehicles over rough surfaces and from one plane to another, it may be rocked to substantially upright position and be held in such position by positioning it as shown by dotted lines in Fig. 2, wherein the rear end portions of the sections 6 at the surfaces thereof which extend uppermost, when the coupler is in 90 coupling position, about the outer face of the trailer 18, the coupler resting at the forward end walls of its slots 8 upon the pivot rod 16 as shown.

The hook-equipped portion of the device 100 is intended for cooperation with a keeper 19, shown as a flat eye presenting the aperture 20, secured to the end of an adjacent trailer vehicle represented diagrammatically at 21, the eye being horizontal and extending outwardly from, and lengthwise of, the vehicle 21.

In the coupling together of the two vehicles the coupler device is swung on its pivot to a position in which the hook 11 110

enters the opening 20 from the top thereof and the coupler assumes the position shown in full lines in Fig. 2, the coupler resting at its surface, represented at 23 and forming the top wall of the opening between the two hooks 11 and 12, upon the adjacent portion of the eye 19.

In accordance with the preferred embodiment of my invention, the space between the front end of the hook 12 and the opposed rear surface of the hook 11 is of such width as to provide a slight amount only of clearance between these parts and the part of the eye 19 which is adjacent thereto, this feature serving to militate against danger of the coupler, in the movement of the vehicles over rough surfaces, jumping out of engagement with the eye. Furthermore the rear concaved surface 14 of the hook 11 and the forward concaved surface 15 of the hook 12 also aid in preventing such disengagement. The concaved surface 14 also serves in case the coupler device jumps upwardly to cause the keeper and coupler device, to resume, under pull, the positions shown in Fig. 2, the surface 14 acting as a camming guide, whereby the point at which draft is communicated to the coupler device from the keeper, is maintained close to the plane of the strips 4 avoiding undue leverage against the coupler. The keeper and hook-portions of the device are so proportioned, as shown, that, whereas the draft upon the coupler is always directed against the rear surface 14 of the hook 11, draft in the reverse movement of the vehicles and exerting a pushing action on the vehicle 18, is directed against its hook 12 only, at its front surface 15, which latter being concaved, as stated and shown, operates to prevent accidental disengagement of the coupler from the keeper and maintains engagement of the keeper with the coupler-device close to the plane of the strips 4.

The various features above referred to, it will be noted, permit of the constructing of the keeper with the minimum amount of material while presenting the full degree of strength required to cause the device to remain in its original condition.

Furthermore, by constructing a coupler device in accordance with my invention, the parts thereof may be manufactured, as by punching or stamping them from flat stock and thereby avoiding casting or forging operations, which not only makes for economy

of manufacture but enables all of the hook-devices to be accurately and uniformly produced.

While I have illustrated and described a particular construction constituting an embodiment of my invention, I do not wish to be understood as intending to limit it thereto as the same may be variously modified and altered without departing from the spirit of my invention.

What I claim as new, and desire to secure by Letters Patent, is:

1. A coupler device formed at one end with a depending portion and a portion in the rear of said first-referred-to portion between which a recess is presented, said recess opening through the bottom of the coupler device and at which portion the device is adapted to receive a keeper, the opposed surfaces of said portions being generally upwardly divergent and the lower end of one of said portions extending below the lower extremity of the other of said portions and extending across and beyond the vertical plane occupied by the inner surface of the latter.

2. A coupler device formed at one end with a depending portion and a portion in the rear of said first-referred to portion between which a recess is presented, said recess opening through the bottom of the coupler device and at which portion the device is adapted to receive a keeper, the opposed surfaces of said portions being concaved and generally upwardly divergent, and the lower end of one of said portions extending below the lower extremity of the other of said portions and extending across and beyond the vertical plane occupied by the inner concaved surface of the latter.

3. A coupler device formed at one end with a depending, relatively slender, lug having a convexed front surface and a concaved rear surface and a portion in the rear of said lug between which latter and said lug a recess is presented, said recess opening through the bottom of the coupler device and at which portion the device is adapted to receive a keeper, the surface of said lug being divergent relative to the latter, the lower end of said lug extending below the lower end of said portion and extending across and beyond the vertical plane occupied by the inner surface of said portion.

FRANK J. REICHMANN.
